UNITED STATES PATENT OFFICE.

WILLIAM H. WOLFRATH, OF NEW YORK, N. Y.

SASH-FASTENER.

SPECIFICATION forming part of Letters Patent No. 238,627, dated March 8, 1881.

Application filed August 5, 1880. (Model.)

To all whom it may concern:

Be it known that I, WILLIAM HENRY WOLFRATH, of the city and county of New York, and State of New York, have invented a new and useful Improvement in Railroad-Car-Sash Manipulators, of which the following is a complete and exact description, reference being had to the accompanying drawings, forming part thereof.

10 This invention relates to sash-fasteners which are operated by a knob, spring, and sliding rod; and it consists in the peculiar construction and combination of parts, hereinafter set forth.

15 Figure 1 represents a side view of a portion of a sash with my fastening devices attached, also a part of the frame with which the fastening-bolt engages. Fig. 2 represents the fastener in perspective, some of the parts being slightly modified.

The fastening-bolt A passes through the side of the sash near its lower end, and is provided with a spring, b, that forces it outward. From the rear end of said bolt a rod, d, extends to 25 the end of a crank-arm, c, carried by the shank of a knob, E. This crank-arm is also provided with a pin, e, which is arranged to engage the

lower end of a lever, e', that is pivoted at its middle, and connected at its upper end to the rear end of a rod, d'. The forward end of said rod is attached to the rear end of bolt A. When said knob is rotated in one direction the draft of arm c on rod d withdraws the bolt. When said knob is rotated in the other direction the action of pin e on lever e' effects the same result through rod d'.

The fastening-bolt may have either a bar-shaped end, as shown in Fig. 1, or a recessed head, as shown in Fig. 2. In the former case it engages with recesses in the frame, and in the other case with a rack attached thereto.

What I claim as my invention, and desire to secure by Letters Patent, is—

In a sash-fastener, the combination of the fastening-bolt A, spring b, and rods d d' with 45 the pivoted crescent-shaped lever e', the crank-arm c, stud or pin e, and knob E, said parts being connected and operated substantially as set forth.

WILLIAM H. WOLFRATH.
